UNITED STATES PATENT OFFICE

1,974,782

GAME APPARATUS

Julius W. Muench, Rochester, N. Y.

Application March 25, 1933, Serial No. 662,795

2 Claims. (Cl. 273—145)

The invention relates to a game apparatus.

The object of the present invention is to provide a simple, practical and inexpensive game apparatus designed for playing various games of chance where a set of dice is employed such as in parcheesi, steeplechase and similar games where the progress is made according to the various spots on a set of dice.

A further object of the invention is to provide a game apparatus of this character where the operation of the dice will be perfectly fair and absolutely beyond the control of the operator with respect to the shuffling of the dice so that cheating will be effectually eliminated and absolute fairness in the manipulation of the dice assured.

With these and other objects in view, the invention consists in the construction and novel combination and arrangement of parts hereinabove fully described, illustrated in the accompanying drawing and pointed out in the claims hereto appended, it being understood that various changes in the form, proportion and minor details of construction within the scope of the claims, may be resorted to without departing from the spirit or sacrificing any of the advantages of the invention.

In the drawing:

Figure 1 is a perspective view of a game apparatus constructed in accordance with this invention.

Fig. 2 is a longitudinal sectional view of the same.

Fig. 3 is a detail perspective view of one of the dice shown in Figs. 1 and 2.

Fig. 4 is a sectional view of the die shown in Fig. 3.

Fig. 5 is a detail perspective view of a die illustrating another form of the invention.

Fig. 6 is a sectional view of the same on the line 6—6 of Fig. 5.

Fig. 7 is a detail perspective view of a die illustrating another form of the invention.

Fig. 8 is a sectional view of the same.

In the accompanying drawing in which is illustrated the preferred embodiments of the invention, 1 designates a receptacle preferably consisting of an oblong box provided with a glass top wall 2 and having vertical side and end walls

3 and 4 and a horizontal bottom 5. The box which is adapted to receive a set of dice 6 is preferably provided with a false bottom 7 to form a relatively shallow dice compartment 8. The false bottom is preferably provided with

vertical supporting portions 10 fitting against the inner faces of the end walls of the receptacle and reinforcing the same, as illustrated in Fig. 2 of the drawing. The supporting portions 10 which constitute attaching portions for the false bottom may be secured to the end walls of the receptacle by an adhesive or any other suitable means.

The set of dice is designed to be made of pith, balsa wood, celluloid or any other material affected or attracted by static electricity which is produced on the glass top wall by rubbing the same with a silk cloth (not shown). The static electricity produced in the glass top wall of the receptacle will attract the dice and cause the same to jump upward from the bottom of the dice compartment to the top wall and in order to prevent them from adhering to the top wall and at the same time to cause the dice to rapidly change their positions the dice are provided at their corners with diagonally disposed projections 11 which space the faces of the dice from the top wall when the dice contact with the top wall.

This will result in the dice jumping up and down a plurality of times depending upon the condition of the weather. In dry weather the static charge will be greater than in weather where the atmospheric conditions are not so favorable and by providing the diagonally disposed points the charge of static electricity will not become exhausted until the dice have jumped up and down a sufficient number of times to insure complete changing of the position of the dice. While the set of dice shown in Figs. 1 and 2 consist of three dice a single die or any other number of dice may, of course, be employed according to the character of game to be played.

In Figs. 1 to 4 inclusive of the drawing each die which is provided with the conventional spots has the diagonally disposed projections 11 formed by concaving the faces of the die. The concave faces of the dice may be of greater or less depth according to the size of the dice and to enable projections of the desired prominence to be provided.

Instead of concaving the faces of the dice to form the diagonal projections, a die as illustrated in Figs. 5 and 6, having flat faces 12 may be employed, and diagonal projections 13 may extend from the corners of the die to prevent the flat faces of the die from coming in contact with the glass top of the receptacle. This will prevent rapid dissipation of the discharge of the static electricity and insure the requisite jumping or movement of the dice.

In Figs. 7 and 8 of the drawing is illustrated a die 14 having the corners cut off and presenting at the corner portions of the die triangular plane surfaces 15 and forming three corners at each of 5 the corner portions of the die. This cutting off of the corners of the die reduces the area of the faces of the die and increases the number of the angles or corners of the die as the die with the corners cut off will have three times as many angles or 10 corners as the ordinary cubical die. These corners contact with the glass top and with the bottom of the die compartment of the receptacle and prevent the die from sticking either to the glass top or to the bottom of the receptacle.

15 In operation the glass top of the receptacle is rubbed with a silk cloth or other suitable material adapted to produce a static charge of electricity on the glass top of the receptacle and the die or set of dice within the dice compartment will be 20 attracted by the charge of static electricity and upon contacting with the glass top will be repelled and a continual jumping of the dice will be produced so that a fair shuffling of dice will be effected without any liability of cheating or unwarranted manipulation of the dice by the player. 25 It will be clear that the element of chance will absolutely control the movement or shuffling of the dice and that the game apparatus is adapted for general use in all games where a set of dice is 30 employed.

What is claimed is:

1. A game apparatus operable under influence of static electricity, comprising a receptacle including a bottom, sides and ends and also a false 35 bottom to form a relatively shallow game element

compartment having a bottom spaced from the bottom of the receptacle and parallel therewith, the end portions of the false bottom being bent and directed upwardly on an incline to near the top edge of the receptacle, the upper ends of said inclined portions of the false bottom being bent downwardly parallel with the ends of the receptacle and secured thereto and forming shoulders at the juncture of said inclined end portions of the false bottom and the said downwardly bent portions, the upper edges of the side and end walls of the receptacle having inwardly directed flanges with the end flanges thereof disposed over said shoulders in spaced relation thereto, and a glass top member for the receptacle and which has its ends arranged between the said shoulders and the end flanges of the receptacles, and game elements within the shallow compartment and arranged to strike against the glass top and the bottom and the included ends of the shallow compartment on each charge of static electricity produced by rubbing the glass top with cloth.

2. A game apparatus comprising a receptacle having a glass top, and static electrically actuated game elements all formed alike as to shape and having flat faces bearing game indicia of different values and including projections adapted to strike against the inner face of the glass top and the bottom of the receptacle so as to prevent the faces of the game elements from contacting directly 105 with the glass top and the bottom of the receptacle, whereby a maximum amount of movement of the game elements will be produced by each charge of static electricity.

CERTIFICATE OF CORRECTION.

Patent No. 1,974,782.

September 25, 1934.

JULIUS W. MUENCH.

It is hereby certified that error appears in the printed specification of the above numbered patent requiring correction as follows: Page 2, line 95, claim 1, for "included" read inclined; and that the said Letters Patent should be read with this correction therein that the same may conform to the record of the case in the Patent Office.

Signed and sealed this 16th day of October, A. D. 1934.

Leslie Frazer

Acting Commissioner of Patents.
